US00D575756S

(12) **United States Design Patent**
Kim et al.

(10) **Patent No.:** **US D575,756 S**
(45) **Date of Patent:** **** Aug. 26, 2008**

(54) **PORTABLE PHONE**

(75) Inventors: **Young-Sae Kim**, Palo Alto, CA (US);
Chi-Young Ahn, Seoul (KR); **Young-Ju Yeo**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/272,251**

(22) Filed: **Feb. 5, 2007**

(30) **Foreign Application Priority Data**

Sep. 29, 2006 (KR) 30-2006-0040062

(51) **LOC (8) Cl.** **14-03**

(52) **U.S. Cl.** **D14/138**

(58) **Field of Classification Search** D14/138,
D14/496, 341-347; 455/575.3, 575.1; D21/517

See application file for complete search history.
